UNITED STATES PATENT OFFICE.

THOMAS CUSDIN, OF ARMADALE, VICTORIA, ASSIGNOR OF ONE-HALF TO
JOHN WILLIAM RICE, OF ARMADALE, MELBOURNE, VICTORIA.

SPRING-HEEL HORSESHOE.

SPECIFICATION forming part of Letters Patent No. 687,605, dated November 26, 1901.

Application filed March 28, 1901. Serial No. 53,216. (No model.)

To all whom it may concern:

Be it known that I, THOMAS CUSDIN, farrier, a subject of the Queen of Great Britain, residing at Orrong road, Armadale, in the Colony 5 of Victoria, have invented new and useful Improvements in Spring-Heel Horseshoes, of which the following is a specification.

This invention relates to a construction of horseshoe devised with the object of diminishing concussion and which consists of upper and lower members welded or riveted together or otherwise united at the toe portion or formed in one piece and divided by sawing or otherwise toward the heel in order to 10 receive interposed elastic cushions of india-rubber or other elastic material, the said members and interposed cushions being securely united by rivets in such manner as to allow full play for the elastic components of 15 the shoe. By this construction the rubber is protected from wear, and all the advantages of elasticity of tread and the consequent avoidance of concussion are obtained without, on the one hand, the disadvantage as regards 20 want of durability which would result were the rubber to be applied on the tread itself or, on the other hand, the disadvantage of loosening of the nails fastening the shoe to the hoof and the injurious effects of rubber 25 applied directly to the sole of the hoof which would ensue were the elastic cushions to be applied between the shoe and the hoof. Furthermore, the metallic tread of the shoe is better adapted to retain road detritus, which 30 concretes in the cavities formed in the tread of the shoe and by its gritty character assists to prevent slipping.

The invention will be described with reference to the accompanying drawings, forming 35 a part of this specification, and wherein—

Figure 1 represents a face view of the tread or under surface of the shoe which comes in contact with the ground. Fig. 2 is an outer side edge view of the shoe, partly in section. 45 Fig. 3 is a cross-section on line 3 3, Fig. 1, drawn to an enlarged scale; and Fig. 4 is a similar cross-section showing the effect of compression of the rubber cushion.

a is the upper plate of thin flat steel which 50 comes next to the hoof, and *b* is the under or tread plate, made of steel of greater thickness

to allow for wear, both plates being shaped to the usual form of a horseshoe and being welded or riveted together or otherwise united at the toe for a suitable distance at either side 55 of the usual toe-clip, the plates *a b* being gradually separated toward the heel ends and the intervening angular spaces being filled with wedge-shaped cushions *c* of vulcanized india-rubber or other elastic material forming 60 a compound elastic shoe. The elastic pads are retained in place partly by downwardly-turned clips *d*, forged upon the upper plate *a* and embracing the rubber cushions at each side toward the heel end, these clips being wide 65 enough apart to admit the heel of the under plate between them when the rubber is compressed. The rubber cushions are, furthermore, retained in position by rivets *e*, which pass through the cushions and whereby the 70 upper and lower plates *a b* are united in such manner as to permit the compression of the rubber cushions under the weight of the animal and of the plates springing apart again to a distance limited by the rivets as soon as the 75 weight is removed. It is an especial object of this invention to permit of this elastic action of the plates and cushions without, on the one hand, any possibility of the rivets being forced upward through the plate *a*, so as 80 to press against and injure the sole of the hoof, and, on the other hand, to avoid all liability of the rivets being bent or broken by contact with stones when, under the effect of compression of the cushions, the rivets are 85 caused to work through and to protrude from the holes in the under plate *b*, through which they pass.

The elasticity of tread obtained by the use of the rubber cushions has the effect not only 90 of diminishing concussion, but of increasing the durability of the shoe, and it is a further object of the invention to provide such a thickness of metal and such an extent of wearing-surface for the under plate as will still 95 further increase the durability of the shoe and insure a better foothold by providing for the retention of road detritus in the wearing-surface in such manner as to improve the foothold on slippery surfaces. With this object 100 the under plate or member *b* is preferably made of uniform thickness, so as to pre-

sent a broad wearing-surface to contact with the ground. It has the usual crease or groove *f* around the outer edge, in which the nail-heads are received, and may be slightly beveled at the inner edge of the forward portion of the shoe. At the places where the rivets *e* are to be inserted cavities *g* are formed in the under surface of the plate *b*, these cavities being conveniently of half-round form in cross-section with straight ends, the depth of the cavities being not less than the maximum amount of compression of the rubber cushions *d*, so that when by such compression the rivets *e* are caused to protrude within the cavities *g*, as shown in Fig. 4, the rivets will always remain housed within the cavities *g* and be protected by the surrounding metal portions of the shoe, so that they can never project so far as to be liable to come in contact with the ground or strike against a stone, which would cause the rivets to become bent or broken, or otherwise interfere with the elastic working of the shoe.

In order to guard against the rivets being forced upward through and caused to project from the upper plate *a*, so as to be liable to cause injury to the hoof, the rivets are of reduced diameter at their upper ends, so as to present shoulders, which bear against the under surface of the upper plate *a* and cannot pass through the countersunk holes in the plate *a* in which the reduced upper ends of the rivets are riveted. The cavities *g* are made of just the necessary length to accommodate and house the rivets, as described, and for the purpose of insuring a good foothold they may be supplemented by additional cavities *h*, of similar form, extending toward the heel ends in continuation of the cavities *g*, but separated from the latter by intermediate solid or bar-like portions *i*, the cavities *h* serving to gather road detritus, which concretes therein and assists to prevent slipping.

Nail-holes *k* are formed through both the upper and lower plates.

The rubber cushions besides affording elasticity of tread act also as insulators to prevent the transmission to the hoof of the heat generated by friction or acquired by contact with a hot pavement. This elastic construc-

tion of shoe is applicable not only to shoes which are open at the heel, as usual, but also to what are known as "bar-shoes," as well as to other special forms of shoe.

Having now particularly described and ascertained the nature of the said invention and in what manner the same is to be performed, I declare that what I claim is—

1. A compound, elastic-tread horseshoe constructed of upper and lower members or plates *a*, *b*, united or formed in one at the toe and separated toward and at the heel by intermediate elastic cushions *c*, the two plates being united by rivets *e* shouldered and riveted at their upper ends to the upper plate *a*, whereby they are prevented from movement in either direction through said upper plate and the lower plate being formed with cavities in its under face in which the lower heads of the rivets are housed, said cavities being of a depth greater than the heads whereby when by the compression of the cushions the rivet-heads are caused to protrude into the cavities, the rivets will be protected by the adjacent walls or solid portions of the plate *b* from contact with the ground or with stones, substantially as specified.

2. A shoe substantially as described having the upper and lower plates and interposed cushion and having the lower plate provided with the cavities *g* to receive the rivets, and additional cavities such as *h* to receive and collect road detritus, the cavities *h* being separated from the cavities *g* by an intermediate cross-bar or solid portion *i*, substantially as specified.

3. A shoe substantially as described provided at its heel with upper and lower plates and cushions between the same and having downwardly-projecting side clips formed on the upper plate near its rear end and extended alongside of and adapted to laterally confine the rear ends of the rubber cushions the said cushions being free to expand rearwardly and also free to expand laterally throughout a major portion of their lengths.

THOMAS CUSDIN.
